OTIS T. GRAHAM AND OAKLEY J. GRAHAM, OF RICHMOND, VIRGINIA

APPARATUS FOR TRANSPORTING CEMENTITIOUS MATERIALS

Application filed February 21, 1929. Serial No. 341,821.

The present invention relates to apparatus for the transportation of cementitious materials, particularly wet concrete mixtures.

It is now becoming generally recognized that, in carrying on building operations in cities or other localities in which the use of considerable quantities of concrete is contemplated, it is advantageous to provide a concrete mixing plant at a centrally located point for mixing concrete under standard conditions, and to then transfer the mixed concrete to the point of ultimate use by means of vehicles, generally motor trucks of the dump body type. Mixing of the concrete at a central plant has many known advantages, both from the economic standpoint and from the point of view of the builder and architect who desire concrete of the highest quality and the lowest price.

It is essential however to utilize, in connection with a central mixing plant and wet concrete distributing system of this type, conveying apparatus in which is incorporated means for agitating the concrete during its passage from the central mixing plant to the particular point of use since, if no such means is provided, the heavier elements of the concrete aggregate, i. e., the stone and the heavier sand grains, will settle toward the bottom of the vehicle body and the lighter elements, i. e., the finer sand grains, the cement, and the water will tend to move toward the top of the mixture. Various types of vehicle bodies for preventing this segregation in transit have heretofore been designed or suggested, but for one reason or another, have not come into public favor.

The present invention contemplates an improved vehicle body provided with such an agitating device and by means of which the wet concrete can be constantly agitated in transit to maintain a perfect mixture throughout the journey, even though it be a relatively long one. More specifically stated the invention contemplates the utilization, in combination with a stationary, that is a non-rotatable, body of the open top type, of a rotary stirring or agitating device by means of which the concrete aggregate is fully protected against segregation and with the ex-

penditure of very little power, which power is preferably taken from the motor which propels the vehicle. It is essential that a body of wet concrete contained in a vehicle body be properly agitated and we have found it quite necessary to provide an agitating means, the stirring elements of which describe paths which follow closely the bottom of the vehicle so that this portion of the mixture contained in the vehicle body can be thoroughly agitated or raked.

In accordance with the present invention the agitating elements move in this prescribed manner while at the same time provision is made for keeping the power consumption at a minimum by placing the drive means for the agitating elements above the level of the wet concrete mixture and supporting the agitating elements therefrom by members which, as they pass through the concrete mixture, offer a minimum surface in the direction of their movements, to contact with the said mixture. The agitating elements are furthermore so designed and constructed that their progress through the mixture cannot be blocked or retarded by stones of large size nor by stones of small size which might become caught between the agitating elements and the wall of the vehicle body. We prefer to employ a vehicle body the inner wall of which is cylindrical, or at least, formed as portion of a solid of revolution, since with this form of body a shaft mounted co-axially with the inner surface of the vehicle body wall may be conveniently employed as a drive means for the agitating elements. The agitating elements may be maintained upon the extremities of radially disposed arms.

This arrangement has been demonstrated to be eminently satisfactory in practice, providing an agitating means of great efficiency at minimum cost to install and to operate, but it will nevertheless be apparent to those skilled in the art that the design and arrangement of the component elements of the invention may be modified to suit conditions, and for bodies of different shapes and drive means of different kinds.

Further objects of the invention are to provide a novel drive means for the agitating

mechanism whereby such mechanism can be conveniently driven from the internal combustion engine, or other motor which constitutes the power motor of the vehicle, and to effect certain improvements in the means for effecting the discharge of the cementitious material from the vehicle body.

In the accompanying drawings:

Figure 1 is a side elevation of portion of a motor truck embodying the above mentioned improvements, the body of the truck being shown in section to more clearly disclose the agitating means;

Figure 2 is a section on line 2—2 of Figure 1, portion of the end of the body being broken away to disclose one of the agitating elements;

Figure 3 is a rear end view of the vehicle body;

Figure 4 is a section on line 4—4 of Figure 3;

Figure 5 is a perspective view of one of the agitating elements;

Figure 6 is a longitudinal section through a truck body equipped with an alternative form of agitating means;

Figure 7 is a section on line 7—7 of Fig. 6; and

Figures 8 and 9 are enlarged views of details of this alternative form of agitating means.

The vehicle chassis is indicated generally at 10 and the body at 11. The details of the chassis are not fully illustrated and need not be herein specifically referred to since any suitable form of chassis may be employed. We contemplate the use of an internal combustion engine as a power plant, which engine is not illustrated, but it will be understood to be of usual type and to have a power take-off shaft by means of which power may be taken for the purpose of operating the agitating means. Mechanism is likewise provided for raising the body 11 relatively to the chassis 10 for the purpose of dumping the contents, but such mechanism forms no part of the present invention and need not therefore be herein specifically described.

The body 11 may be conveniently fabricated of sheet metal and is formed with a semi-cylindrical bottom, or bottom which comprises portion of a solid of revolution. The end walls 11' and 11² are flat vertically disposed members extending transversely of the axis of the bottom and the rear wall 11' is provided with a discharge aperture through which the contained cementitious material may be discharged when the body is tilted rearwardly. This discharge aperture is normally closed by a door 12 hingedly connected to the rear wall 11' by horizontally disposed hinges 13. Normally the door 12 is prevented from swinging about the hinges 13 by means of wedges 14, of which there may be any necessary number, which wedges are

passed through suitable apertures in the curved angle irons 15 secured to the margins of the door 12 and also through suitable registering apertures in the correspondingly curved angle irons 16 which are rigidly secured to the cylindrically shaped bottom of the body 11. The hinged door 12 is centrally apertured at 17 to provide a relatively small discharge orifice which may be employed in the event that it is desired to discharge a portion only of the contents of the body 11, passage of such material through this discharge opening being controlled by a vertically movable door or gate 18, the vertical edges of which are guided in slots formed by the margins of the end wall 12 of the body adjacent the sides of aperture 17, the filler pieces 19 and the angle irons 20.

Secured to the door 18, and adjacent the vertical edges thereof are parallel vertically disposed racks 21 and meshing with these racks respectively are pinions 22 rigid with the transverse shaft 23 revolvably mounted in suitable bearings 24 and provided with an operating handle 25. By rotating shaft 23 by means of the operating handle the gate 18 may be raised or lowered.

Disposed longitudinally of body 11 is a power shaft 30, the axis of which is co-incident with the axis of curvature of the body 11 and the ends of which are rotatably supported in end bearings 31 secured to the end walls of the body and center bearing 32 which is supported by a transverse bridging member or brace 33 having its ends rigidly secured to the side walls of the body. The forward end of shaft 30 projects through the forward wall 11² of the body and into a gear casing 34 bolted to the body, this shaft end having rigidly mounted thereon a bevel gear 35 which meshes with a second bevel gear 36 likewise contained within the casing 34, which gear is operatively connected to the power motor of the vehicle by means which will hereinafter be more fully described. Agitating elements are indicated generally at 40, there being four of these for the type and size of body shown in the drawings but the number of which may be varied at will to suit conditions. Each such agitating element includes a member 41 which may conveniently be an angle iron as shown in Figure 5, disposed longitudinally of the body and parallel to the shaft 30, and a plurality of radially disposed agitating blades 42 adjustably secured thereto.

Each such agitating blade comprises a flat base portion 42' provided with a central longitudinal slot 42² through which securing bolts 43 may be passed. These securing bolts 43 also pass through circular holes in the supporting member 41 and it follows that the blades 42 may be adjusted in the direction of their lengths through limited distances, that is, they may be adjusted radially of shaft 30.

The portions of the agitating blades 42 which project outwardly from members 41 are of reduced cross sectional area and are pointed at their ends as shown. They are furthermore so formed as to present cutting edges 42³ in the direction of their movement. Conveniently the agitating blades are formed of flat malleable metal and the projecting portions are twisted relatively to the base 10 portions 42' so as to present corners in the directions of movement, which corners constitute the cutting edges heretofore referred to. The outer pointed ends of the agitating blades describe, in the operation of the machine, circular paths concentric with the inner surface of the body 11 and substantially equi-distant therefrom, the points of the blades very closely approaching the body, yet not touching at any point.

20 Members 41 are secured to the outer ends of radial arms 50, the inner ends of which are fixed on shaft 30. These radial arms are adjustable in length, each being formed in two sections, a section 50' rigid with shaft 30 and a section 50² rigid with member 41. The sections are secured together by bolts 51 passing through registering apertures in the two sections, the apertures of one section constituting cylindrical holes, and of the other section elongated slots, so that the members 41 may be bodily adjusted radially of shaft 30. The radial arms 50 are of rectangular cross section and are disposed so as to offer a minimum surface to contact with the cementitious material contained in the body 11 when shaft 30 is rotated.

The four agitating elements which are arranged 90° apart, successively pass through the material contained in the body. The agitating blades 42 thoroughly rake that portion of the material which is located next adjacent the wall of the body and prevent the accumulation of heavy materials along the bottom. The blades are so spaced apart that the largest stones used in mixing the concrete may pass freely therebetween so that they are kept clear at all times. Inasmuch as they are pointed at their outer ends it is impossible for stones to become wedged between the ends of the blades and the wall of body 11. If for any reason one or more of the blades become bent it will be obvious that the distance between the point of the blade and the wall of body 11 will be increased, because of the original radial disposition of the blades, so that it will not be possible for any blade to come in contact with the wall through bending.

As the blades wear they may be outwardly adjusted either individually or in groups of four. The radial arms 50 which support the agitating elements are opposed by the material in the body with the minimum of frictional retardation and substantially all of the power which is transmitted to the shaft 30

is expended in agitating the cementitious material which lies close to the curved bottom of the body, which portion requires the greatest amount of agitation since the heavy particles of the mixture tend to immediately deposit themselves there.

The bevel gears 35 and 36 within casing 34 transfer motion to the horizontal shaft 30 from the vertically disposed power shaft 55. The ends of this power shaft 55 are rotatably supported in bearings 56 and 57. The lower end of shaft 55 is provided with a clutch block 58 forming one portion of a separable coupling indicated generally at 59 and intermediate the ends of the shaft are provided a frangible connection 55' and a universal connection 60 which need not be herein described in detail as they are fully disclosed in our co-pending application Ser. 257,925 filed February 29, 1928.

A clutch block 61 mounted upon the chassis cooperates with clutch block 58 on the ends of shaft 55 and by means of this separable connection, which is also fully disclosed in our co-pending application above referred to, it is quite possible to break the power line between the motor and the agitating mechanism when the truck body 11 is raised and to re-establish the connection automatically when the truck body is lowered. A reduction gearing is diagrammatically illustrated at 62, being rigidly mounted upon the chassis. One element of this gearing is connected to clutch block 61 and another to a sprocket 63 connected by a chain 64 to a second sprocket 65 mounted upon the end of shaft 66. Shaft 66 is connected, through a universal joint 67, and clutch 68, to the power take-off of the engine (not illustrated). The clutch 68 is operable by means of a hand lever 69 conveniently positioned relatively to the driver's seat so that the agitating mechanism may be readily brought into operation or disconnected from the engine. This power connection between the shaft 30 and the engine is substantially the same as disclosed in our co-pending application previously referred to, with the exception however that the speed reduction gearing is located wholly upon the chassis instead of upon the vehicle body. It is not necessary therefore to elevate a relatively heavy speed reduction gear in dumping the truck.

In Figures 6, 7, 8 and 9 a somewhat different style of agitating mechanism is illustrated. Here the main shaft 80 has three pairs of arms 81 extending radially therefrom, the angle between consecutive pairs of arms being 120°, instead of 90° as in the case of the agitating mechanism first described. The outer ends of each pair of arms are connected together by parallel spaced cross members 82, the ends of which may be welded, or otherwise suitably secured to the arms. The cross members are arranged so as to present

their edges to the concrete aggregate as the shaft 80 revolves in the direction of the arrow, Figure 7. Secured to each such cross member, as by welding, is a series of short angle members 83, these angle members being equidistantly spaced along the several cross members, and also being so arranged that radial lines passing through the angle members of one cross member will also pass through the angle members mounted on the associated cross member. Each pair of angle members, considering them to be grouped along radial lines, supports an agitating blade 84, the blades being slotted and the angle members being provided with circular holes through which bolts 85 extend, the blades being thereby adjustably secured to the cross members. The blades are formed substantially in the same manner as the blades employed in connection with the first described form of agitating mechanism and need not be specifically described.

As an added safeguard against breakage of the driving mechanism in the event, however remote, that one of the teeth should be caught, the bolts 85 which secure the inner ends of the teeth respectively, to the associated angle members, are made only sufficiently strong to withstand the ordinary strains incident to agitation. Should the progress of a tooth be very materially retarded, as by striking an indentation of the body or being caught by a stone wedged between the wall of the body and the point of the tooth, the said bolt will break, thus permitting the tooth to rock about its outer point of support. Each outer tooth securing bolt is likewise designed to break under unusual load or distortion and as a result its breakage will immediately follow that of the corresponding inner bolt, and as a result the obstructed tooth will entirely break off of the frame to which it is attached should its progress be seriously impeded. Replacement of a tooth so dislodged may obviously be easily accomplished.

The operation of this form of agitator is very similar to that of the form first described. The shaft 80 rotates in the direction of the arrow and the three agitating frames pass successively through the aggregate. The strata of concrete next to the wall of the body is thoroughly agitated and with a minimum expenditure of power due to the fact that the surface which each agitating element presents to the concrete, in the direction of its movement, is not great. The teeth are so spaced apart that even the largest stones which may be expected to be found in the concrete will not lodge between them.

In the operation of both this form of agitating mechanism and that first described it is found that the successive passage of the agitating elements through the wet aggregate results in a surging movement of the concrete longitudinally of the body to a limited

extent. Thus the agitating mechanism exerts a kind of kneading action on the wet aggregate which is highly beneficial in promoting its complete admixture. When an agitating element descends upon passing into the concrete it forces some of the mixture ahead of it in its passage and leaves a depression behind. The concrete ahead of the element flows, to a limited extent, toward the ends of such element. In rear of the element the concrete flows, to a limited extent inwardly toward the center of the path described by the said element. This surging movement, or kneading, of the wet aggregate improves its quality, as does the straight mechanical stirring or agitation to which the aggregate is subjected.

It is of course contemplated that truck bodies of various capacities may be equipped with agitating means and other devices embodying the principles of this invention which may necessitate changes in the design and arrangement of its component parts. Furthermore the specific shape of the body may be changed as desired. Also the structure of the agitating elements may be changed slightly where it is desired to agitate concrete mixtures which depart from the ordinary standard mixtures for which the agitating mechanism illustrated was particularly designed. The invention is not limited therefore to the exact mechanism described and illustrated by way of example.

Having thus described the invention, what is claimed as new and desired to be secured by Letters Patent is:

1. In a vehicle for transporting cementitious materials comprising a chassis having a motor, a body having agitating means therein, a power line connecting said motor and agitating means whereby the power of the motor may be utilized in operating said agitating means, said power line including a separable coupling, whereby the body may be raised relatively to the chassis in dumping, and reduction gearing, the said reduction gearing being positioned wholly upon the chassis.

2. The combination with a vehicle body designed and constructed for the transportation of cementitious materials, the bottom of which has the shape of a portion of a solid of revolution, and means for agitating that portion of the cementitious material carried in said body which lies adjacent the bottom thereof, said means including a shaft rotatably supported in said body and disposed with its axis co-incident with the axis of the curved portion of the bottom of the body, a plurality of axially spaced radially disposed and relatively short agitating blades remote from said shaft, a plurality of frames to which said blades are secured in groups, and means supporting the frames from said shaft, the means securing each tooth to its associ-

ated frame being frangible, whereby the tooth may be detached when it meets with excessive resistance.

3. The combination with a vehicle body designed and constructed for the transportation of cementitious materials, the bottom of which has the shape of a portion of a solid of revolution, and means for agitating that portion of the cementitious material carried in said body which lies adjacent the bottom thereof, said means including a shaft rotatably supported in said body and disposed with its axis co-incident with the axis of the curved portion of the bottom of the body, a plurality of axially spaced radially disposed and relatively short agitating blades remote from said shaft, a plurality of frames to which said blades are secured in groups, and means supporting the frames from said shaft, each frame comprising two spaced parallel cross members, and each tooth being adjustably secured to two of said members.

4. The combination with a vehicle body designed and constructed for the transportation of cementitious materials, the bottom of which has the shape of a portion of a solid of revolution, of means for agitating the material carried therein comprising blades adapted to be moved transversely of the vehicle bottom below the normal level of the material therein, and means for supporting and moving said elements transversely of the vehicle bottom along circular paths close to and concentric with the bottom, said means comprising a shaft revolvably mounted in the body and having its axis coincident with the axis of the body, arms radiating from the said shaft, members arranged parallel to the axis of the body and rigidly secured to the radial arms, said agitating blades being secured to the members and projecting radially outwardly therefrom, each blade comprising a flat strip having a pointed outer end, each blade being twisted so that it presents an inclined surface to the direction of movement thereof through the material.

In testimony whereof we hereunto affix our signatures.
